ABSTRACT OF THE DISCLOSURE

Fire control apparatus for use in xerographic fusing zones. The apparatus includes an ultraviolet detection tube positioned in the area to be sensed for flames. It is electrically coupled to a valve to control the flow of fire extinguishing CO₂ into the area being sensed. The electric circuit acts to release a pulse of CO₂ upon the sensing of a flame by the detecting tube. After the termination of the pulsed flow of CO₂, the circuit returns to its original state for a second flame sensing to allow supplemental pulsations and sensings until the flame is extinguished.

This invention relates to fire control apparatus, and, in particular, to apparatus for the detecting and extinguishing of fires in areas such as xerographic fusers.

More specifically, this invention relates to apparatus for detecting the presence of a flame at a xerographic fusing station and for extinguishing the flame with the required number of pulses of fire extinguishing fluid to put out the flame.

In the xerographic process a plate comprising a layer of photoconductive material on a conductive backing is given a uniform electric charge over its surface and then exposed to the subject matter to be reproduced by various projection techniques. This exposure discharges the plate in accordance with the light intensity reaching it thereby creating an electrostatic latent image on or in the plate.

Development of the image is effected by developers which comprise, in general, a mixture of suitable resin based powder, hereinafter referred to as toner, and a carrier material which functions to carry and to generate triboelectric charges on the toner. The function of the carrier material is to provide mechanical control of the toner, or to carry the toner to an image surface, and simultaneously provide almost complete homogeneity of charge polarity. In the development of the image, toner powder is brought into surface contact with the photoconductive layer and is held thereon electrostatically in a pattern corresponding to the electrostatic latent image. Thereafter, the developed xerographic image may be transferred to a support material to which it may be fixed by any suitable means.

As the science of xerography has progressed, faster automatic xerographic reproducing machines have been developed, thus necessitating improved fixing apparatus capable of fixing the toner powder image to the support material at a rate compatible with the higher speed machines. In fixing the toner powder to the support material it is desired to obtain the highest possible quality of reproduction from the original document. One such fixing apparatus is disclosed in copending application Ser. No. 585,971 filed Oct. 11, 1966 in the names of Gilbert A. Aser et al. For convenience of illustration the invention of this application will be described with reference to its use therein, although it is not to be limited thereto.

In the apparatus disclosed in the above cited copending application, it has been found desirable that a sheet of support material passing through the fixing apparatus be closely sensed to quickly detect the presence of flames caused by the high temperature of the fuser acting on the

2

toner image and backing sheet. It is also essential that any detected flame be quickly extinguished before it damages the fusing elements of the xerographic reproducing machine generally.

Conventional fire sensing apparatus is insufficient for the purposes of the instant application. For example, a photocell could not be used due to the incandescence of the radiant energy creating mechanisms of the xerographic fuser. A thermistor also could not be used due to the high temperature at which the fuser normally operates. Furthermore, conventional systems have insufficiently fast response times for the purposes needed in the instant system.

In the same manner, a flame detector responsive to actuate an unlimited supply of fire extinguishing fluid is undesirable. This is because excess fluid such as CO₂ would contaminate the area and require a cleaning after each fire detection.

The present invention is in flame control apparatus including an ultraviolet sensor capable of energizing a circuit and thus pulsating a small amount of fire extinguishing fluid upon the detection of a flame. The system is self-capable of returning to its original state after the pulsation for resensing and repulsing of the fluid until the flame is extinguished. No excess fire extinguishing fluid need be used beyond that needed for extinguishing the flame. Consequently, the apparatus of the instant invention is economical and clean in addition to being dependable and quick.

It is, therefore, an object of the instant invention to extinguish flames in an area such as a xerographic fuser.

It is a further object of the instant invention to sense an area for the presence of a flame and to extinguish any flame sensed in the area.

It is a further object of the instant invention to project a pulse of fire extinguishing fluid into an area being sensed for flames.

It is a further object of the instant invention to project a pulse of fire extinguishing fluid into an area being sensed for flames and to continue projecting pulses of the fluid only until the flame is extinguished.

It is still a further object of the invention to improve xerographic fusing apparatus by sensing the fusing zone for flames and for extinguishing any flames which may occur.

These and other objects of the present invention are achieved by apparatus including a detector in the form of an ultraviolet detection tube positioned in the area to be sensed for flames. It is electrically coupled to a valve to control the flow of fire extinguishing CO₂ into the area being sensed. The electric circuit acts to release a pulse of CO₂ upon the sensing of a flame by the detection tube. After the termination of the pulsed flow of CO₂, the circuit returns to its original state for a subsequent flame sensing to allow additional pulsations and sensing until the flame is extinguished.

For a better understanding of the invention, as well as other objects and further features thereof, reference is had to the following detailed description of the invention to be read in conjunction with the accompanying drawings, wherein:

FIG. 1 is a diagrammatic side, cross-sectional view of a xerographic machine adapted for continuous and automatic operation embodying the fire control system of the instant invention;

FIG. 2 is a front enlarged view of the fusing source and shields viewed in the direction of arrows 2-2 of FIG. 1, and

FIG. 3 is a circuit diagram used in the fire control system of the instant invention.

Shown in FIG. 1 is a xerographic machine constructed for continuous and automatic operation and embodying

the principles of the instant invention. All of the processing stations referred to by letters are conventional in the xerographic art except for the fire control elements adjacent the fusing station which form the basis of the instant invention. For the purposes of the present disclosure, the several xerographic processing stations in the path of movement of the xerographic drum may be described as follows:

A charging station A, at which a uniform electrostatic charge is deposited on the photoconductive layer of the xerographic drum;

An exposure station B, at which the light or radiation pattern of copy to be reproduced is projected onto the drum surface to dissipate the charge in the exposed areas thereof to thereby form a latent electrostatic image of the copy to be reproduced;

A development station C, at which a xerographic developing material including toner powder having an electrostatic charge opposite to that of the latent electrostatic image, is moved into contact with the drum surface, whereby the toner powder adheres to the latent electrostatic image to form a xerographic powdered image in the configuration of the copy being reproduced;

A transfer station D, at which the xerographic powdered image is electrostatically transferred from the drum surface to a transfer material or a support surface;

A drum cleaning station E, at which the drum surface is brushed to remove residual toner particles remaining thereon after image transfer, and

A fusing station F, at which the toner image is permanently affixed to the backing sheet.

For a more detailed description of this machine, reference is had to U.S. Patent No. 3,301,126 to Robert F. Osborne et al.

As shown in FIG. 1, paper which is removed from the xerographic drum-shaped surface 10, is fed by a conveyor belt 12 toward the fusing station F. After passing through the fuser area it moves by supplemental conveyor belts 14 into a copy catch tray 16 associating with exterior of the machine for collection by the operator.

In the fusing station F is a preheat roller 18 and a shielded radiant fusing element 20. These elements, insofar as they have been described, are substantially the same as that described in the aforementioned application to Aser et al. Located behind the reflector shield portion 22 of the radiant fusing element is a second backing plate 24 shaped similar to the shield portion 22 of the radiant fusing element. Between these two plates is a cavity 26 which functions with apertures 28 to permit the movement of a fire extinguishing fluid such as CO₂ into the fusing area. Centrally located on the backing plate 24 is an aperture communicating with conduits 130 which interconnects the cavity with a supply bottle 32 of fire extinguishing fluid which is kept under pressure. A valve 34 is located on the conduits for selectively permitting the flow of CO₂ from the bottles 32 to the fuser station F. The valve is adapted to be opened or closed through the action of solenoid SOL-1 which in turn is activated and inactivated through the action of the contacts CR1 and CR2 of contact relay 1CR. The operation of these elements is more fully described in the description of the circuit of FIG. 3 hereinbelow.

Also located adjacent the fusing zone F is the ultraviolet detecting tube 36. This tube, which may be of the type, for example, commercially available from the Ampere Corporation under the name of Amperex Electron Tube 155 UG, is adapted to remain non-conductive during normal operation. When it is subjected to a source of ultraviolet radiation, however, it turns conductive. It is this type of a device physically located within the area being sensed and electrically coupled to the circuit which controls the solenoid and operation of the valve 34 that permits the flow of fire extinguishing fluid into the area being sensed upon the detection of a flame.

The circuit for effecting the proper timed operation of the fire extinguishing fluid is shown in FIG. 3. As explained above, the circuit is adapted to actuate the solenoid SOL-1 to open and close valve 34 to get a pulsated flow of CO₂ from the supply bottle 32 through conduits 5 to the fuser area being sensed.

Solenoid SOL-1 is actuated through control relay 1CR. This relay has three contacts CR-1, CR-2 and CR-3. CR-1 is a normally closed contact which, when open, holds CR-2 closed. CR-1 is normally held closed during the conventional operation of the xerographic machine. But when a flame is detected in the fuser area, the control relay 1CR reverses the condition of the contacts to permit the opening of CR-1 to thereby actuate the solenoid SOL-1, open the valve 26 and consequently permit the flow of CO₂ to extinguish the flame. After a predetermined time of flow of CO₂ the control relay 1CR is released to return its contacts to its first or original position and thus deenergize SOL-1, close valve 34 and consequently terminate the flow of CO₂. With the circuit in its original state, a resensing of the fuser area for the continued presence of a flame is made. If a flame is still present, it is detected and a supplemental discharge of CO₂ is made in the manner described above. This continues until, and only until, the flame is extinguished.

It should be pointed out here that the existence of a flame is invariably accompanied by a stoppage of normal paper flow through the fuser area. This stoppage acts to terminate the paper feeding and other xerographic machine functions in the manner set forth in copending U.S. Patent application 585,972 filed Oct. 11, 1966 in the name of Larry Wood.

The instant circuit is composed of five major sections as shown in FIG. 3 and designated generally as 44, 46, 48, 50, and 52. The first area 44 is the power generating section which converts the standard 110 volt AC input into the proper DC wave shape and determines the maximum peak DC. This is necessary to operate the rest of the circuit and control the minor time delay section 48, 40 to be later described.

Section 46 is the fire extinguishing actuation section which includes relay contacts CR-1 and CR-3 which trip SOL-1 and consequently controls the opening of valve 34 for permitting the flow of CO₂. CR-3 is opened and closed when the relay 1CR is tripped between its two positions. The opening and closing of CR-3, in turn, activates solenoid SOL-1 to open and close valve 34 and flow the fire extinguishing fluid. This section also includes the UV detector 36 also shown in FIG. 1, but which acts in this capacity as a functioning part of the circuit. The above mentioned minor delay section is noted as 48. This circuit section prohibits minor UV detections by detector 36 from tripping the control relay 1CR. Such minor UV detection might be caused by random photon excitations in the form of cosmic radiation in proximity to the detector 36. These excitations are generally in the order of a few milliseconds and it is not desired to flow the CO₂ into the fuser area upon their presence. Consequently, this section acts, in conjunction with the power generating section 44 to filter out the effects of UV photon excitations in the fuser area. This section, thus only allows extended UV excitations, longer than a few milliseconds, as would be caused by a flame, to trip the control relay CR-1. This section thus only operates when the UV presence exceeds an extended duration of time, as for example, in the order of 50 milliseconds.

The fourth section of the control circuit 50 is the relay actuating section and includes the contact relay 1-CR. This section also includes silicon controlled rectifiers Q3 and Q4, or similar threshold switching means, one of which must always be conducting when the circuit is in its second or CO₂ dispensing state. The conducting of one or the other of the controlled rectifiers acts to hold the relay in its second position to reverse its contact and 75 consequently permit the flowing of CO₂.

The final section of the circuit is the major timing section 52. This circuit section is operational only after a fire has been detected and the CO₂ employed for extinguishing it. This circuit section acts when energized to return the circuit to its original or first state after a pre-determined pulsation of CO₂, as for example, three seconds.

When the circuit of the instant invention is rendered operative through the application of suitable power through lines 38 and 40, only the power generating section 44 is carrying current. This is because detector 36 is non-conductive due to the absence of UV detection. Consequently, no power is brought into the fire extinguisher actuation section 46, minor time delay section 48, or control circuit section 50. In like manner, at this time, relay contact CR-2 is open prohibiting the flow of power into the major time delay section 52 of the circuit. Current normally attempts to flow through the control circuit section 50 including the contact relay 1-CR and SCR Q3 and Q4. However, there is no power on the gates of these SCR's and consequently they act to render this portion of the circuit open to prohibit a current flow through the relay.

When, however, an extended presence is detected by detection tube 36, the circuit is closed through this portion of the circuit to bring a current through amplifying transistors Q1 and Q2 to thereby activate the gate of SCR Q3 and permit a flow of current through the contact relay 1-CR. This tripping of the relay reverses the state of the relay contacts CR-1, CR-2 and CR-3. With contact CR-1 open, no further current can go to the gate of Q3 since this portion of the circuit is now open. However, the opening of contact CR-1 is accompanied by a closing of contact CR-2 to bring power through the major time delay section 52 of the circuit. This acts to energize the gate of this CR Q4 to render Q4 conducting and permit the continuance of the current flow through relay 1-CR. When the time constant for the major time delay section of the circuit has been reached, all power will flow into the gate of SCR Q5 to render that portion of the circuit conducting to thereby short out the power to the gate of SCR Q4. When this occurs the gates of Q3 and Q4 have each been rendered inoperative to thereby cause the stoppage of current flow through the relay. This returns the circuit to its original state by closing CR-1 and opening CR-2.

The use of capacitor C2 in parallel with resistor R8 allows for minor UV detections by bulb 36 from energizing the gate of Q3 at an undesirable time. Capacitor C2 is chosen so that minor energization of this leg of the circuit will bleed off short conductances of tube 36 as may be caused by random photon excitations.

More specifically, the instant circuit is rendered operational simultaneously with the activation of the xerographic reproducing machines in which it is to be operated. Power enters the circuit through lines 38 and 40. Line 42 is a common ground. The power acts to bring the circuit into its first state where it is ready to sense a fire in the fusing area. Line 38, in conjunction with ground line 32, brings power through diode D1 which gives a preliminary rectification to the 110 volt AC of the power input line. Diode D1 and resistor R1 are positioned in series with three parallel circuit lines. Of these three parallel circuit lines, the first contains a capacitor C1, the second a resistor R2, and the third a gang of three Zener diodes, D2, D3 and D4. In the preferred embodiment, D2 and D3 and D4 are substantially of equal value and act together to determine the maximum or peak DC voltage to be obtained. R1, C1, and R2 determine the wave shape output. A sawtooth wave is desired to permit effective operation of the minor time delay portion of the circuit and proper tube operation. Power is in this portion of the circuit during all time portions of machine operation, when a flame is to be sensed. Further flow of power is prohibited by non-conducting detector tube 36 and open relay contact CR2.

Located in series with resistor R1 on line 30 is the UV detector 36 and the normally closed contact CR-1 of relay 1-CR. CR-1 is held closed as a result of 1-CR not being energized while the detector is not responding to the presence of a flame. Resistors R3 and R4 are in series with the detector and contact CR1. R3 and R4 are separated by a lead into Q1, Q3 for proper power input into the transistor Q1 and supplemental portions of the circuit.

When the detector 36 becomes conductive due to the presence of ultraviolet in its vicinity and with power being supplied thereto, transistors Q1 and Q2 act as an amplifier to charge capacitor C2 through resistor R7. When C2 becomes charged to a sufficient voltage the silicon controlled rectifier Q3 conducts power through relay 1CR to thereby reverse its orientation and permit contact CR1 to open and the CO₂ to extinguish a flame. When the detector 36 does not sense UV, it remains non-conducting and the DC voltage remains below this conducting value because capacitor C2 discharges through resistor R8. But with extended UV present, i.e., a flame being detected, C2 becomes sufficiently charged to turn on the silicon controlled rectifier Q3 to energize 1CR and fire this portion of the circuit.

Diode D5 rectifies the AC input to relay 1CR from line 40. Resistor R9 in series with diode D5 acts to limit the initial surge of power into the SCR Q3 during operation. Located between Q3 and R9 in parallel with one another are capacitors C3 and the contact relay 1CR. C3 functions to hold in the relay during negative half cycles of current. Zener diode D6 raises the voltage level required to permit firing of SCR Q3 to thus assist in prohibiting minor time delays from switching the relay. With Q3 is conducted, tripping the relay 1-CR, CR3 and SOL-1, and activating the major timing section of the circuit. Thyrector D9 couples the relay actuating section 50 with the return line or ground 42. D9 functions to remove the effect of transients or spikes from the system in the conventional fashion.

With the relay CR1 tripped, Q3 is rendered inactivated while Q4 is rendered conductive to actuate the major time portion of the circuit. This is because closed contact CR2 brings power to this portion of the circuit. Diode D7 is in series with parallel resistors R11 and R12. These elements are in series with parallel combination of Zener diode D8 and capacitor C5. This combination provides a constant DC voltage from line 38 when this portion is energized. Normally open contact CR2 links this voltage shaping section of the circuit with the uni-junction timing circuit. The uni-junction timing circuit includes uni-junction transistor Q6 which functions in conjunction with resistors R16, R17, R18, R19 and R20 as well as capacitors C4 to permit the retention of this portion of the circuit operative for the desired time, as for example, three seconds. This time can be varied easily since resistor R20 is variable. As can be understood, this portion of the circuit can only be energized through the closing of CR2 and CR3 along with the tripping of SOL-1 which is effected by the switching of relay 1CR.

Under normal conditions, the gates of SCR Q3 and Q4 would tend to remain energized after initial energization. But in the instant circuit, diode D5 passes half-wave rectified current through relay 1CR and the SCR's which allow the forward potential on the anode end of the SCR's to go to zero. Thus when the current through Q3 and Q4 goes to zero with no power on the gates, the SCR's return to a non-conducting or blocking state.

Serially located resistors R13, R14 and R15 represent a biasing circuit to permit energization of SCR Q4 after the energization of relay 1CR. SCR Q5 becomes activated by the timing circuit to short the biasing circuit of Q4 after the elapse of the three second timed interval. This shorting acts to terminate the conduction of SCR Q4 to permit, in conjunction with the previous inactivation of

SCR Q3, the return of the contact relay 1CR and the entire circuit to its original state. Supplemental sensings by the detector 36 in the above-described fashion continue until the flame is extinguished.

It can thus be seen that the disclosed embodiment defines a system for controlling fires in a xerographic fusing zone. It is a dependable system, quickly responsive to the occurrence of flames and effective for the control thereof.

While the present invention, as to its objects and advantages, has been described herein as carried out in a specific embodiment thereof, it is not desired to be limited thereby; but it is intended to cover the invention broadly within the scope of the appended claims.

What is claimed is:

1. Fire control apparatus comprising, in combination, 15
flame sensing means positionable in an area to be controlled for flames, said flame sensing means including a bulb having an electrically non-conducting capacity under normal conditions but having an electrically conducting capacity when exposed to ultraviolet 20
conditions,
conduit means linking the area to be controlled with a supply of fire extinguishing fluid,
valve means to selectively open and close the conduit means to permit or prohibit the flow of fire extinguishing fluid to the area to be controlled and 25
control means coupling the flame sensing means and the valve means to permit the flow of a predetermined pulse of fire extinguishing fluid upon the detection of a flame by the flame sensing means, said control means also including minor time delay elements to retain the valve means closed during exposure of the flame sensing means to short duration ultraviolet conditions as caused by cosmic radiation.
2. Fire control apparatus comprising, in combination, 30
flame sensing means positionable in an area to be controlled for flames,
conduit means linking the area to be controlled with a supply of fire extinguishing fluid,
valve means to selectively open and close the conduit means to permit or prohibit the flow of fire extinguishing fluid to the area to be controlled and 35
control means coupling the flame sensing means and the valve means to permit the flow of a predetermined pulse of fire extinguishing fluid upon the detection of a flame by the flame sensing means, said control means including major time delay elements to return the control means to its initial flame sensing condition after a predetermined timed flowing of fire extinguishing fluid caused by the detection of a flame.
3. The apparatus as set forth in claim 2 wherein said control means further includes a control relay having a first and second threshold switching means in parallel to each other and coupled to one terminal of the control relay with the gate of the first of said threshold switching means coupled to said flame sensing means for energization thereby to trip said relay and open said valve in response to flame detection, and with the gate of said second threshold switching being coupled to said major time delay elements for energization thereby to retain said relay and said valve open until the elapse of a predetermined time whereupon the gate of said threshold switching means is deenergized to return said relay and said valve to their original states.
4. For use adjacent a xerographic fusing zone, apparatus to control unwanted flames therein comprising:

an ultraviolet flame detecting tube which is normally non-conductive during the absence of ultraviolet radiation and conductive during the presence of ultraviolet radiation as caused by a flame,

conduit means linking the fusing zone with a supply of fire extinguishing fluid,

a valve in the conduit means selectively operable in a first position wherein the conduit is closed to prohibit a flow of fire-extinguishing fluid into the fusing zone and operable in a second position wherein the valve is open to permit a flow of fire extinguishing fluid to the fusing zone,

circuit means coupling the valve and the detecting tube, said circuit means being normally held in a first state during the absence of ultraviolet radiation to retain the valve in its first or closed position, said circuit means being activated into a second state upon the conduction of said detecting tube as caused by the ultraviolet radiation of the flame in the fusing zone to switch the valve into its second state for causing a flow of fire extinguishing fluid into the fusing zone,

said circuit means also including a major time delay portion to return the circuit to its first state after a predetermined time pulsation of fire extinguishing fluid whereby said circuit terminates the flow of fire extinguishing fluid and is then again operative to resense the fusing zone for continued ultraviolet radiation of the flame.

5. The apparatus as set forth in claim 4 wherein said circuit means also including a minor time delay portion to render said circuit inoperative to switch from its first state to its second state upon the detection of extremely short pulses of ultraviolet radiation as caused by cosmic radiation.

6. Fire control apparatus including, 40
flame sensing means responsive to ultraviolet radiation and positioned in an area to be sensed,
conduit means linking the area to be sensed with a supply of fire extinguishing fluid,
valve means to selectively open and close said conduit means to permit or prohibit the flow of fire extinguishing fluid to the area to be sensed,
control means coupling said flame sensing means and said valve means to permit the flow of fire extinguishing fluid upon the detection of ultraviolet radiation from a flame by said flame sensing means and means to render said flame sensing means incapable of actuating said control means upon the detection of ultraviolet radiation of short durations.

7. The apparatus as set forth in claim 6 and further including means to return said valve means to a state prohibiting the flow of fire extinguishing fluid after a predetermined quantity of fire extinguishing fluid has flowed to the area to be sensed.
